UNITED STATES PATENT OFFICE.

MITCHEL YEGANIAN, OF NEW YORK, N. Y.

CORSET.

Application filed June 10, 1922. Serial No. 567,358.

To all whom it may concern:

Be it known that I, MITCHEL YEGANIAN, a citizen of Armenia, residing in the borough of Manhattan, in the city, county, and State 5 of New York, have invented certain new and useful Improvements in Corsets, of which the following is a specification.

My invention relates in general to articles of personal apparel and more specifically to 10 corsets.

The primary object of my invention is to make a corset having a plurality of separate lacing units capable of being adjustably united in a manner to permit the laces of all 15 of said units to be instantly and simultaneously tightened to close the corset on the form.

Another object of the invention is to unite the ends of one set of laces of one lacing unit 20 to one portion of a belt member, and unite the opposing set of ends of the same lacing unit to another portion of a belt member, and unite each set of ends of the laces of each other lacing unit to separate members 25 and adjustably attach said members to the belt members in a manner to permit the top or bottom portions of the corset to be varied as to the distance said portions may be opened or closed on the form to be fitted.

Another object of the invention is to arrange the lacing units in such manner that in whatever position the members uniting the ends of each unit are adjusted on the belt members, the pull on said belt members 35 to tighten the laces in each unit will be directly around the waist line.

I am aware that corsets employing a plurality of laces having their ends united on a common belt member in a manner to have 40 all of said laces simultaneously drawn by the common belt member to tighten said corset, are old, but in all the forms disclosed but one unit of laces is controlled by the common belt member. Other lacing units 45 have been added but they are either operated by a separate belt member or the standard form of lacing has been employed. The present invention allows of any desired adjustment of the upper or lower lacing unit 50 to increase or decrease the opening at the top or bottom of a corset, and by pulling a common belt member close the corset around the form in the desired manner.

Other and further objects, including cer- 55 tain features of construction will appear in the specification and be pointed out in the

appended claims, reference being had to the accompanying drawings which show the preferred embodiment of my invention.

In the accompanying drawings:

Figure 1 is a view in rear elevation showing the laces tightly drawn to uniformly close the corset.

Figure 2 is a front view of the same on a smaller scale showing the belt fastened after 65 the laces have been tightly drawn.

Figure 3 is an enlarged detail view of the devices for securing the ends of the separate lacing units to the belt.

Figure 4 is a detail section on the line 70 4-4 Figure 3.

Figure 5 is a rear elevation of the corset showing the bottom lacing unit adjusted to allow the corset to be opened wider at the 75 bottom than the top.

Figure 6 is a similar view to Figure 5 showing the top lacing unit adjusted to allow the corset to be opened wider than at the top than the bottom.

In the preferred embodiment of my invention the corset comprises two body sections 1 and 2 of any desired shape or style. These two sections meet in the front where they are reinforced by members 3 and 4 to which are attached the well known form of clasps 80 5 and 6 for fastening said sections together in the usual manner, and if desired said sections may be closed at the top thereof by adding hooks and eyes, as shown at 7. The back meeting edges of the two body sections 90 are provided with reinforcing strips 8 and 9, each strip in turn being provided with a plurality of eyelets. These eyelets are divided into groups marked 10, 11 and 12 and are also, arranged in pairs and disposed oppositely to each other for the purpose hereinafter explained.

Extending partially around the top of the upper edge of each body section and fastened to said body sections by a line of 100 stitching, is a portion 13. These portions 13 are preferably made of elastic webbing, or other like material, and are intended to make the corset more readily and comfortably fit the form.

Each body section may be provided about its lower edge with suitable hose supporting members 14, which, however, are of the ordinary construction and form no part of the present invention.

The laces are divided into a plurality of units with a plurality of laces in each unit.

In the drawings I have shown a center lacing unit and a top and bottom lacing unit. The top lacing unit comprises four laces, the center lacing unit six laces and the bottom lacing unit eight laces. Of course it should be understood that these lacing units may comprise any number of laces desired and I do not confine myself to the exact number and arrangement of the laces shown in each unit.

The eyelets 10 of the top unit are adapted to receive laces 15 the oppositely disposed ends of which are united and each set attached to a separate strip of webbing 16 by stitching or other suitable means. I have shown each lace 15 as passing from a strip of webbing 16 through an eyelet in the opposite body section, crossing and passing through the eyelet next below in the other body section, and thence to the other section of webbing 16 of the same unit. While this is deemed the preferred form of lacing other disposition of the laces through the eyelets may be employed.

The eyelets 11 in the center lacing unit receive laces 17 therethrough in the same manner as the top unit, the ends of one set of laces of said center lacing unit are united and attached to one portion of a belt member 18 while the opposite set of ends of said center lacing unit is united and attached to a second portion of a belt member 19. The ends of the laces in this unit are attached to the belt members in any desired manner. These belt members are of sufficient length to pass completely around the body sections 1 and 2 and overlap a sufficient distance to allow them to be fastened together. The manner of fastening the ends of the belt members together may be of any desired kind but I have here shown a standard form of buckle 20. In order to prevent the overlapping end of one of said belt members from hanging down, I employ a keeper or other suitable device 21.

The eyelets 12 of the bottom lacing unit receive therethrough laces 22 in the same manner as the above described lacing units, the oppositely disposed ends of which are united and each set attached to a separate strip of webbing 23 in the same manner and for the same purpose as the laces in the top unit.

Fastened to each of the belt members 18 and 19, adjacent the end to which the laces 17 of the center lacing unit are attached, is a keeper 25, preferably made of a single piece of metal having prongs 25' which protrude through the belt member and are pressed down to firmly hold said keeper in the desired position.

Carried on each belt member 18 and 19, a short distance from the keeper 25, is a buckle 26, which is employed to fasten the

strips of webbing, to which the laces of the top and bottom lacing unit are attached, to the belt member after the lacing units have been adjusted to meet the requirements of the wearer. These strips of webbing 16 and 23 of the top and bottom lacing units pass through the keepers 25 and thence through the buckle 26, where they are firmly held in the manner shown in Figure 1. Of course, it should be understood that the particular form of keepers and devices for fastening the strips of webbing to the belt members may be of any style or kind suitable for the purpose.

To apply the corset to the normal form, the strips of webbing are first adjusted so that the united ends of the laces of the top and bottom lacing units are equi-distant from the keepers on the belt members, in which adjusted position said strips of webbing are held by the buckles 26, in the manner shown in Figure 1. The back meeting edges of the body sections are then pulled apart, the laces of each unit passing freely through their respective eyelets until the back opening is enlarged a sufficient distance to permit the corset to be easily placed around the form, after which the front meeting edges of the body sections are clasped in the usual manner. The belt members are then drawn tightly around the waist line in turn uniformly pulling the laces of all units and causing the back meeting edges of the body sections to close in approximately parallel relation. After the laces have been drawn as tightly as desired the ends of the two belt members are buckled together to hold said laces permanently in the position obtained.

To adjust the corset to fit the form when the same is abnormal below the waist line, the lacing units are freed in the manner above described. The strips of webbing holding the bottom unit of laces are then released and the bottom of the back meeting edges of the body sections drawn apart a sufficient distance to allow the corset to properly fit the form, that is, so that the back meeting edges of the body sections will be open wider at the bottom than the top, assuming the position shown in Figure 5. The strips of webbing are then fastened to the belt members by the buckles 26 and the corset placed in position on the form, after which the laces are drawn and the ends of the belt members buckled together in the same manner as described for the normal condition.

To adjust the corset to fit the form when the same is abnormal above the waist line, the lacing units are freed in the manner hereinbefore described. The strips of webbing holding the top unit of laces are then released and the top of the back meeting edges of the body sections drawn apart a

sufficient distance to allow the corset to properly fit the form, that is, so that the top of the back meeting edges of the body sections will be open wider at the top than the bottom, assuming the position shown in Figure 6. The strips of webbing are then fastened to the belt members by the buckles 26 and the corset placed in position on the form, after which the laces are drawn and the ends of the belt members buckled together in the same manner as described for the normal condition.

What I claim is:

1. In a corset having sectional portions 15 with eyelets adjacent the opening edges of said portions, a center lacing unit having a plurality of laces engaging the complementary eyelets in the center of said portions, a top lacing unit having a plurality of laces 20 engaging the complementary eyelets in the top of said portions, a bottom lacing unit having a plurality of laces engaging the complementary eyelets in the bottom of said portions, a divided belt member, the end of 25 one portion having attached thereto all the ends of the laces on one side of said center

unit, one end of the other portion of said belt member having attached thereto all the ends of the laces on the opposite side of said center unit, tabs for uniting the ends of 30 each group of laces in the top and bottom lacing units, and means for adjustably attaching said tabs to the belt members.

2. A corset having sectional portions with 35 eyelets adjacent the opening edges of said portions, a center lacing unit engaging the eyelets in the center of each of said portions, a top lacing unit engaging the eyelets in the top of each of said portions, a bottom lacing unit engaging the eyelets in the bottom of each of said portions, a belt member fastened to the opposing ends of the center lacing unit, tabs for uniting the opposing ends of the top lacing unit, tabs for uniting the opposing ends of the bottom lacing unit, 40 and means carried by the belt member for uniting said belt member and the tabs, whereby said top and bottom lacing units will have independent adjustment with relation to the center lacing unit.

MITCHEL YEGANIAN.
